US0D1056259S

(12) **United States Design Patent** (10) Patent No.: **US D1,056,259 S**
(45) Date of Patent: ** Dec. 31, 2024

(54) **STRUCTURAL PANEL**

(71) Applicant: **Franz Neuhofer**, Zell am Moos (AT)

(72) Inventor: **Franz Neuhofer**, Upperaustria (AT)

(**) Term: **15 Years**

(21) Appl. No.: **35/518,139**

(22) Filed: **Jul. 31, 2023**

(80) **Hague Agreement Data**

Int. Filing Date: **Jul. 31, 2023**

Int. Reg. No.: **DM/230787**

Int. Reg. Date: **Jul. 31, 2023**

Int. Reg. Pub. Date: **Aug. 25, 2023**

(30) **Foreign Application Priority Data**

Feb. 14, 2023 (EM) 015011447-0001
Feb. 14, 2023 (EM) 015011447-0003
Feb. 14, 2023 (EM) 015011447-0004
Feb. 14, 2023 (EM) 015011447-0005
